UNITED STATES PATENT OFFICE.

DANIEL S. KOONS AND WILLIAM F. MOUGHLER, OF CHICAGO, ILLINOIS.

BRUSH.

SPECIFICATION forming part of Letters Patent No. 634,527, dated October 10, 1899.

Application filed September 21, 1898. Serial No. 691,552. (No model.)

To all whom it may concern:

Be it known that we, DANIEL S. KOONS and WILLIAM F. MOUGHLER, citizens of the United States, residing at Chicago, in the county of Cook and State of Illinois, have invented certain new and useful Improvements in Self-Cleansing Brushes; and we do hereby declare the following to be a full, clear, and exact description of the invention, such as will enable others skilled in the art to which it appertains to make and use the same.

Our invention relates to a novel construction in a fountain bath-brush, the object being to provide a simple, durable, and efficient device of this character; and it consists in the features of construction and combinations of parts hereinafter fully described and claimed.

In the accompanying drawings, illustrating our invention, Figure 1 is a top plan view of a brush constructed in accordance with our invention. Fig. 2 is a longitudinal section of same on the line 2 2 of Fig. 1. Fig. 3 is a longitudinal section showing the application of the fountain devices to another form of brush.

Fig. 4 is a detail sectional view, on an enlarged scale, of the valve shown in Figs. 1 and 2. Fig. 5 is a fragmentary bottom plan view showing the water-outlet from the brush.

Referring now to said drawings, A indicates a brush having a back C, in the middle or center of which is an opening 1, and adjacent the ends is provided with recesses 2. Said brush A is adapted to be secured to a false back B, which is provided with a central water-passage 3, having a screw-threaded opening or outlet 4, which is adapted to receive the hollow shank 5 of a screw 6, passing through said opening 1 in said back C, whereby the latter is secured to said false back B, said recesses 2 in said back C being adapted to receive dowels on said back B to hold these members rigidly in relative position. The head of said screw 6 is provided with a plurality of radial passages communicating with the central passage in said shank 5 and form water-outlets. In this manner said screw 6 performs the double function of securing the back C to the back B and for connecting the water-passage in the back B with the brush proper. The flow of water to said brush is controlled by means of a valve 7, having a projecting stem 8, adapted to be operated by

the finger to open said valve and admit water to the brush. Said valve is held normally closed by means of a spring 9 and also by the water-pressure, as will be obvious.

In brushes having a handle 11 the latter is made telescopic, and to this end comprises two members 12 and 13, the former of which is rigid with the back B and forms a continuation of the water-passage in said back B, while the member 13 is of larger diameter and receives said member 12 and is telescopically movable thereon, a water-tight joint being effected between said members by means of a stuffing-box of ordinary construction, detailed description of which is omitted.

Said brush is connected with the water-supply by means of a flexible hose 14, which is attached to a mouthpiece 15 on the brush or a similar mouthpiece 16 on the handle 11, the inside diameter of the latter being sufficiently large to permit the passage of the hose therethrough, so that the connection can be made directly with the brush, as shown in full lines, Fig. 2, or with the handle, as shown in dotted lines in Fig. 2.

In Fig. 3 we have illustrated a modified form of our brush, which likewise consists of a brush A', having a back C' and a false back B' mounted thereon, the latter being hollow and provided with a central water-passage a, from the center of which an outlet b leads in the shape of an internally-screw-threaded pipe, which is adapted to receive the hollow stem of a nozzle c, which serves as a means for securing the backs B' and C' together. At one end said back B' is provided with a short hollow stem d, to which a hose e is adapted to be secured and from which said water-passage a is adapted to be fed. Between said stem d and the outlet b said water-passage a is provided with an annular shoulder f, which serves as a valve-seat for the valve g, the stem h of which passes through the contraction of said water-passage thus formed and through the other end of the back B'. A spring i is interposed between the shoulder f and a collar j on said valve-stem h and serves to hold said valve normally closed. Obviously by pressing the projecting end of said valve-stem inwardly said valve g will be opened and admit water to the portion of the passage a on the other side of

said shoulder *f*. A strap *h* is secured at the sides of said back *B'* and passes over the latter, so that by inserting the hand between said back *B'* and said strap *h* the brush can 5 be firmly held and the fingers at the same time kept in position to operate the valve.

We do not of course limit ourselves to the use of this brush for purposes of bath only, as it can obviously be advantageously used 10 for other purposes.

We claim as our invention—

1. In a bath-brush, the combination with a brush, and a false back adapted to be secured thereto and provided with a water-passage, 15 of a screw having a hollow shank and a radially-perforated head adapted to secure said brush to said false back and serve as an outlet for the water in said water-passage, substantially as described.

2. In a bath-brush, the combination with a brush, and a false back adapted to be secured thereto and provided with a water-passage, 20 of a screw having a hollow shank and a radially-perforated head adapted to secure said brush to said false back and serve as an outlet for the water in said water-passage, substantially as described.

25

let for the water in said water-passage, means for connecting said water-passage with a source of supply of water, and a valve interposed in said connection, substantially as described.

3. In a bath-brush, the combination with a brush, and a false back adapted to be secured thereto and provided with a water-passage, 30 of a screw having a hollow shank and a radially-perforated head adapted to secure said brush to said false back and serve as an outlet for the water in said water-passage, means for connecting said water-passage with a source of supply of water, and a valve interposed in said connection, said valve being on 35 said brush and normally closed and adapted to be opened by means of the pressure of a finger on its stem, substantially as described.

In testimony whereof we affix our signatures in presence of two witnesses.

DANIEL S. KOONS.

WILLIAM F. MOUGHLER.
